CLAIM

The ornamental design for a top cap combined with front control for a door panel of a dish treating appliance, as shown and described.

DESCRIPTION

FIG. 1 is a front perspective view of a top cap combined with front control for a door panel of a dish treating appliance showing our new design;

FIG. 2 is a front view of the top cap combined with front control of FIG. 1;

FIG. 3 is a right side view of top cap combined with the front control of FIG. 1, with the left view being a mirror image; and,

FIG. 4 is a top view of the top cap combined with the front control of FIG. 1.

The broken lines in the figures illustrate the portions of the design that form no part of the claimed design.

1 Claim, 4 Drawing Sheets
